UNITED STATES PATENT OFFICE.

GEORGE THOMPSON, OF GRAND RAPIDS, MICHIGAN.

CAR-DOOR.

1,159,550.

Specification of Letters Patent.

Patented Nov. 9, 1915.

Application filed May 1, 1915. Serial No. 25,139.

To all whom it may concern:

Be it known that I, GEORGE THOMPSON, a citizen of the United States of America, residing at Grand Rapids, in the county of Kent and State of Michigan, have invented 5 certain new and useful Improvements in Car-Doors; and I do hereby declare the following to be a full, clear, and exact description of the invention, such as will enable 10 others skilled in the art to which it appertains to make and use the same.

This invention relates to auxiliary doors or what may be known as service doors adapted to be secured to and used with the 15 usual sliding door of a freight car. In practice when freight cars are used to carry grain or other loose produce it is usual to board up the openings at the doors to a freight car to the height to which the produce 20 extends, the boards at each end bearing against the backs of vertical frame members which form part of the construction of the car at the door openings. The doors thereupon may be readily moved back and 25 forth the same as though the car was empty.

It is the object and purpose of my invention to eliminate this use of lumber, practically all of which after once being used is shattered and rendered unfit for further use 30 when the car reaches its destination and is emptied. To this end I have provided the construction disclosed in the accompanying drawings, the novel and useful functions of 35 which will appear as further understanding of the disclosure is had.

In the drawings: Figure 1 is a front elevation of a freight car door equipped with my invention. Fig. 2 is a vertical section taken on the line 2—2 of Fig. 1. Fig. 3 is a 40 horizontal section on the line 3—3 of Fig. 1. Fig. 4 is a rear elevation. Fig. 5 is a view similar to Fig. 2 but with the parts in different position; and Figs. 6 and 7 illustrate in section and rear elevation, respectively, details of construction used in embodying my invention.

Like reference characters refer to like parts throughout the several views of the drawings.

50 The car is indicated at 1 and has a floor only such portions of the car and floor being shown as are necessary for the disclosure of the invention. The opening into the car is normally closed by a door 2 which is hung by hangers 3 from a rail 4, the lower edge 55 of the door operating back and forth be-

tween the car and rollers 5 as shown in Figs. 1, 2 and 5. A frame comprised of vertical and horizontal members 6 is secured to the rear side of the door, said members being secured at the upper, lower and side edges of 60 the door as shown.

At each side of the opening into the car which the door is normally designed to close is a vertical post 7. A plurality of elongated 65 loop-like members are pivotally attached to the rear side of the door 2, each member being comprised of a bar 8 lying closely adjacent the door, a bar 9 parallel to and spaced a distance from the bar 8 and ends 70 connecting the ends of bars 8 and 9. If desired one or more intermediate bars 11 may be interposed between the bars 8 and 9, for the purpose of reinforcing the structure. Bars 8 are pivotally secured to the door 2 75 by means of clips 12.

The auxiliary door comprises in its construction three vertical plates 13, 14 and 15 which are secured to the rear bars 9 of the 80 loop-like members heretofore described by means of clips 16. Plates 13 and 14 lie in the same plane while the plate 15 lies back of and is rigidly connected to the plate 14 near one edge, its other edge overlapping one edge of the member 13. It is designed that the 85 two plates 13 and 15 of this auxiliary or service door shall have relative movement with respect to each other and to the door 2 and the clips 16 are sufficiently loose to permit the lateral movement of the parts on the bars 9. A plurality of chains 17 are secured at 90 one end to the door 2 and extend to the rear as shown in Fig. 3 being permanently secured at their other ends to the parts 13 and 14 respectively.

Lugs 18 project forward one from each of the members 13 and 14 being interiorly screw-threaded to receive the ends of the screw 19. It will be observed that one end of the screw 19 is provided with right hand threads while the other is provided with left hand threads. The middle portion of the screw is formed so as to readily receive an operating wrench as shown at 20, this part lying between the spaced apart end 21 of a 100 member 22 which is hinged to a plate 23 permanently secured at the rear side of the door 2. The ends of the screw 19 pass through the spaced apart members 21. An opening 24 is made in a door 2 through 110 which a wrench may be inserted for the operation of member 19, it being apparent that

upon such operation taking place the parts 13 and 14 of the auxiliary or service door may be drawn toward each other or forced away from each other as desired. The opening 24 through the door 2 is closed by a slide 25 carried between guides 26 fastened on the front of the door 2.

A chain 27 or other suitable flexible connection is attached at one end to plate 13 10 passing therefrom through an opening in the door 2 and through a plate 28 secured on the front side of the door. A lever 29 is pivotally connected to the plate and carries an eye 30 to which the other end of the chain 15 27 is attached. A hook 31 is pivotally mounted on the member 30 and is adapted to be inserted through the staple 32, driven into door 2, when the handle 29 is in the position shown in Figs. 1 and 2, an opening 20 in the handle permitting it to pass over the staple so that when the hook is received in the staple the handle is held permanently in lower position.

The operation of the construction so far 25 as described may now be set forth.

When the car is empty the auxiliary construction including the plates 13, 14 and 15 is designed to be located in close proximity to the rear side of the door 2. To effect this 30 the slide 25 is opened to permit access to the nut 20 which is thereupon operated to draw plates 13 and 14 toward each other far enough that their outer edges will come between the posts 7. By grasping the handle 35 29 and forcing it to lower position as shown in Figs. 1 and 2 the auxiliary structure including plates 13, 14 and 15 is elevated and drawn forward, the loops connecting door 2 with this auxiliary construction turning 40 about the axis of their rods 8 as will be clear from the foregoing description. The entire construction will thereupon be received within the limits of the frame provided by the members 6. The handle 29 is held in 45 place by hook 31 engaging staple 32 and the entire structure thereupon may be moved back and forth on the track 4 the same as any sliding door.

When it is desired to use the auxiliary 50 door in the shipment of grain or other loose produce, the handle 29 is released and plates 13, 14 and 15 take the position shown in Fig. 5, being located slightly back of the rear faces of posts 7. By operation of the member 19 plates 13 and 14 are thereupon moved away from each other, the outer edges passing back of the posts 7. As this operation proceeds the chains 17 assume the diagonal position best shown in Fig. 3 and serve to 55 draw the edges of plates 13 and 14 tightly against the post 7 making a very tight engagement that will prevent any loss and insure against the passage of anything between the plates and the post.

60 65 In filling a car with grain or the like the

doors at each side are closed and the auxiliary doors positioned as shown in Figs. 3, 4 and 5, in the manner just described. An elongated opening 33 is provided in the upper portion of the door 2 through which the grain spout from an elevator extends for entering the grain into the car, the grain being entered into the car until it fills the car substantially the height of the plate 13, 14 and 15. When the car is filled the opening 33 may be closed by means of the closure 34 hinged to the door 2 as shown.

I have cut an opening 35 adjacent the lower edge of the door 2 which normally is closed by the plate 36 slidable in guides 37. Back of this in the plate 13 an opening 38 is cut which may be closed by a similar slide 39. When the car is to be unloaded slides 36 and 39 are moved to one side and the grain flows through the openings thus provided. Furthermore by operating the parts 13 and 14 toward each other so that the edges come within the inner sides of the posts 7 the auxiliary door as a whole may be raised, the pressure of the grain behind it tending to help this operation, after which door 2 may be moved to one side, the pressure thereon tending to obstruct this movement being relieved as it flows through the opening 35.

From the foregoing it will be apparent 95 that I have provided an auxiliary or service door which may be used time after time for an indefinite period. The plates 13, 14 and 15 are of steel and rods 8, 10 and 11 may also be of steel or any other suitable material. The construction thus made is very durable 100 and is reinforced in all particulars so as to be able to withstand the pressure against it when in use. When not in use it lies tightly against the back of the door and occupies 105 little or no space. It may be applied to car doors already in use or it may be built on to new doors as new cars are constructed. There are few parts, none of which are at all complicated or liable to get out of order 110 and all of which are fully capable of withstanding the rough usage to which freight cars and doors are subjected. Various modifications in detail may be resorted to without departing from the invention which is defined in the appended claims, the invention including all modifications in structure falling 115 within their scope.

I claim:—

1. In combination, a car door, means for 120 slidably mounting the door, plates located back of the door and in the same vertical plane, an additional plate connected to one of the plates and overlapping the other plate, elongated loops lying between and 125 pivotally connected to the door and said plates, chains interposed between and connected to the doors and plates adjacent their vertical edges, screw-threaded lugs projecting forward one from each plate, a member 130

having spaced apart ends pivotally connected to the rear side of the door, a double-threaded screw having a central section adapted to be operated by a wrench, said section being located between the spaced apart ends of said member, and the ends of the screw passing through said spaced apart ends and the lugs, a flexible connection secured to one of the plates and passing 10 through the door, a handle pivotally connected to the front of the door, a connection between the said flexible connection and the handle between its ends, a hook pivotally mounted on the handle, and a staple secured 15 to the door over which the handle is adapted to pass and with which the hook engages in one position of the handle.

2. In combination, a car door, a pair of plates located back of the door and in the 20 same plane with each other, means secured to one plate and overlapping the other, pivotal connections between the door and plates whereby the plates may be brought closely adjacent the rear side of the door or spaced 25 a distance therefrom, chains diagonally positioned between the door and plates, screw-threaded lugs attached one to each plate, a double threaded screw interposed between and passing through the lugs, means connecting the door and screw for causing a simultaneous movement of both plates with 30 reference to the door on operation of the screw, a flexible connection secured to one of the plates and passing through the door, a handle pivotally secured to the door to which the flexible connection is attached, and means for holding the handle against 35 the door after operation thereof to elevate the plates.

40 3. In combination, a car door, a pair of plates located back of the door and in the same plane with each other, an extension plate, one plate overlapping the other plate, pivotal connections between the door and 45 plates whereby the plates may be elevated and brought closely adjacent the rear side of the door or spaced a distance therefrom, chains secured to and between the door and plates, means for moving the plates toward 50 and from each other laterally and simultaneously with reference to the door, a flexible connection secured to one of the plates and passing through the door, a handle pivotally mounted on the front of the door to which 55 the flexible connection is secured, and means for holding the handle in place against the influence of the weight of the plates after operation of the handle to elevate the plates.

4. In combination, a car door, a laterally expansible and contractible auxiliary door 60 back of the car door, pivotal connections between said car and auxiliary doors whereby the auxiliary door may be elevated and brought closely adjacent the rear side of the door or spaced a distance therefrom, means 65 for expanding or contracting the auxiliary door, and means to hold said auxiliary door in elevated position.

5. In combination in a car, vertical posts positioned one at either side of an opening 70 in the car, a door slidably mounted on the car adapted to close the opening, a laterally expansible and contractible auxiliary door pivotally connected to the car door, said pivotal connections permitting the positioning 75 of the auxiliary door in elevated position adjacent the car door or in lower position a distance back of the car door, means for expanding the auxiliary door so that its vertical edges pass behind the posts or contracting it to come within the inner sides of the posts, and means to automatically bind the said auxiliary door against the rear sides of the posts as it is expanded.

6. In combination in a car, vertical posts 85 positioned one at either side of an opening in the car, a door to close the opening, an auxiliary door located back of the car door, means connecting the car and auxiliary doors whereby the auxiliary door may occupy a lower position a distance back of the car door, or be elevated closely adjacent to the car door, means to expand the auxiliary door laterally so that its vertical edges will 90 pass back of the posts and flexible connections between the car and auxiliary doors 95 serving to bind the auxiliary door against the posts as it is expanded.

7. In combination, a car door, a frame connected to the rear side of the door, a laterally expansible and contractible auxiliary door located back of the car door, elongated loop members lying between and pivotally secured to the car and auxiliary door, means to expand or contract the auxiliary door, 100 flexible connections interposed diagonally between and secured to the car and auxiliary doors, means to elevate the door and means to hold it in elevated position.

In testimony whereof I affix my signature 110 in presence of two witnesses.

GEORGE THOMPSON.
